FRANK C. ANDERSON, OF CINCINNATI, OHIO, ASSIGNOR TO THE AMERICAN VALVE
AND METER COMPANY, OF CINCINNATI, OHIO, A CORPORATION OF OHIO.

SWITCH-STAND LATCH.

1,253,200.

Specification of Letters Patent. Patented Jan. 15, 1918.

Application filed October 4, 1917. Serial No. 194,706.

To all whom it may concern:

Be it known that I, FRANK C. ANDERSON, a citizen of the United States, and a resident of Cincinnati, in the county of Hamilton 5 and State of Ohio, have invented certain new and useful Improvements in Switch-Stand Latches, of which the following is a specification.

My invention relates to switch-stands of 10 the low-down type in which the lever is thrown in one direction or the other parallel with the track to open or close the switch, and is held down when completely thrown in either direction by a suitable latch.

15 The object of my invention is to make such switch-stands as this reliable and yet of simple and inexpensive construction.

My invention consists in the combination of parts and in the details of construction 20 and arrangement of parts as will hereinafter be more fully described and claimed.

In the drawing:

Figure 1 is a general perspective view of 25 a switch-stand provided with latches constructed according to my invention; and

Fig. 2 is an enlarged side elevation of one of these latches, as I prefer to construct them.

The switch-stand comprises the casing 1 30 inclosing suitable well-known mechanism by which a vertical shaft 2 carrying the target 3 above and a crank 4 below is given a turn through a substantial angle by means of a horizontal shaft 5 and lever 6 fixed to said 35 shaft 5 and thrown through an angle of substantially 180°; the crank 4 being connected to the point-rail 7 by a connecting rod 8. These details being well-known are deemed 40 sufficiently illustrated in the perspective view.

As is well understood, the lever 6 rests substantially horizontally in either one of the positions to which it is thrown and has a head 9 which forms a handle and also acts 45 as a weight to hold the lever down.

This weight 9, however, is not always to be depended upon to hold the lever 6 down, and frequently under heavy traffic, the lever 6 will be thrown over allowing the switch 50 point-rails, such as the rail 7, to assume a wrong position and thereby derail one or more cars.

As is also well known, latches have been provided to hold the lever 6 in either one of 55 its positions and which latches are usually provided with means for locking them so

that unauthorized persons cannot change the position of the switch. When the latch is locked it may, of course, be relied upon to hold the lever 6 down. But it is highly desirable that such latches be so provided that they automatically open to receive the lever 6 as it is brought down in throwing the switch and then close over it to hold it down. It has also been found highly desirable to provide means whereby the switchman may open the latch with his foot since he frequently holds in one hand some necessary article, generally a lantern, and must use the other hand to throw the lever 6. 60 However, an objectionable result of this provision in many latches that have been produced is the possibility of accidental release of the latch when it has not been locked due to accidental striking of the treadle provided 65 for opening the latch with the foot; as for instance, when a switchman alights from a moving car and chances to step on the treadle. Where the lever 6 lies in the latch loosely, such accidental opening of the latch 70 is of no consequence; but generally the parts are so connected that when the lever 6 is entirely down in its latch, it is holding one or the other of the point-rails such as the point-rail 7 very tightly against the stock-rail 10 75 with the thin end part of the point-rail 7 slightly bent under the strain, and, by its resiliency ready to pull the connected lever 6 out of the latch as soon as the latch is opened. The same tendency results from 80 the strain on one or the other point-rail caused by the cars passing thereover. It will readily be seen that in the case above instanced, the switchman alighting from a car and accidentally opening the latch by 85 stepping on the latch treadle is very liable to cause derailment of the car from which he has just alighted and which is then passing over the rails of the switch and imposing 90 a strain upon them which will cause the rails to move to a wrong position if the lever 6 is released from the latch.

I provide for guarding against such dangers as these, while at the same time not making the latch appreciably more complicated in construction, and while leaving it 95 practically as convenient for operation under the conditions hereinbefore alluded to.

In the latch as I prefer to construct it, there is the housing 11, the lower part of 100 which has an upright slot entirely through it and through which slot extends the latch-

bar 12 with a pivotal mounting 13 on a horizontal axis through the flanking sides of the housing 11. At one end this bar 12 has the weight 14 integral with it outside the rear 5 of the housing 11 and at its other end it has the treadle 15 integral with it outside the front of the housing 11. Between its pivot 13 and the treadle 15, it has extending up from it and integral with it the hook 16; the 10 upper part of the front of the housing 11 being also slotted. To the rear in its upper part, the housing has the crotch 17 which receives the lever 6 down in it with the nose 18 of the hook 16 extending over the bar 6 15 when drawn backward by the action of the weight 14 on the latch-bar 12 and hook 16. The part of the housing in front of the crotch 17 extends up higher than the part 19 at the rear, and this front part has the 20 forwardly extending ear 20 with an opening 21 that the hook 16 lies just rearward of when the latch is closed with the nose 18 lying over the bar 6, as just described. Thus, the latch may be locked by passing the 25 keeper of a suitable lock through the opening 21. The lower rear part 19 has its inner forward side inclined to permit the lever 6 to readily slide down into the crotch 17, even though the lever have some slight displacement as it approaches the latch; it being understood that such slight displacement is due to the slight amount of end-play or 30 looseness in the bearings incident to the practical mounting of the shaft 5 of the 35 switch-stand.

The upper side of the nose 18 is inclined downwardly and rearwardly, so that as the lower side of the lever 6 strikes it, the hook 16 is forced forwardly to admit the lever 6 40 to the crotch 17; this forward movement raising the weight 14 and the weight causing the hook 16 to bring its nose 18 back over the lever 6 after the lever has passed below the nose. For opening the latch, the treadle 45 15 is depressed by engagement of the switchman's foot; raising the weight 14 and drawing the hook 15 with its nose 18 forward away from the top of the lever 6, so that the lever 6 may be raised out of the crotch 50 19. It will be seen that any accidental stepping on this treadle 15 will thus open the latch if there be nothing to prevent the free forward movement of the hook 16.

As before stated, this forward movement 55 will be prevented if the latch has been locked by the padlock having its keeper passing through the opening 21 in the ear 20. But as is well-known, the latch for convenience of use in switching, is often left unlocked, 60 so that the accidental opening in the manner hereinbefore described may occur at any time.

In my improved latch, this accidental opening is prevented by a downwardly extended lug 22 on the rear lower corner of 65

the nose 18 having a substantially straight forward side, and having its lower and rear sides inclined or curved, as is readily seen in Fig. 2. In this view, the full lines and the cross hatching represent the section of the 70 lever 6 when it is resting on the bottom of the crotch 17 as it will when not under strain, or when it has been pushed down by pressure on it or on its head 9, overcoming 75 the strain imposed upon it; and the dotted lines indicate the lever 6 when it is pressing up against the under side of the nose 18 in such a manner that were the nose 18 pulled off the upper side of the lever 6, the lever would fly up out of the crotch 17 making 80 possible the disastrous results hereinbefore alluded to.

It will be seen that with the lug 22 provided according to my invention, the nose 18 cannot slide forward off the lever 6 when the lever 6 is bearing up against the nose, because the front side of the lug 22 will engage with the rear side of the lever 6 near its top. It will be seen that when the lever 6 is thus held up against the lower side of the 90 nose 18 under any of the influences hereinbefore mentioned, the only way in which the hook 16 can be pulled forward to draw its nose 18 away from the top of the lever 6 and permit the lever 6 to be raised is to first depress the lever in the crotch 17, so that its upper side lies below the lower end of the lug 22, whereby the hook with this lug 22 may swing freely forward across the upper side of the lever 6. Thus, it will be seen at 100 all times when there would be danger of the switch flying open as a result of accidental opening of the latch as by accidental stepping on the treadle 15, or other accident, this accidental opening of the latch is prevented on account of the raised position that the lever 6 assumes under such conditions.

While accidental opening of the switch under these conditions is very effectively guarded against, the construction of the 110 latch is hardly appreciably more complicated since the added constructional detail consists solely of this lug 22 added to the end of the nose 18. Furthermore, the latch is practically as conveniently opened by the 115 switchman using one foot and one hand as is any of the latches heretofore used. All the added operation necessary is a slight downward pressure on the head 9 by the hand of the switchman while the foot is 120 borne on the treadle 15; so that as soon as the upper side of the lever 6 passes below the lower end of the lug 22, the hook 16 will be drawn forward by the foot pressure permitting the lever 6 to then be raised out of 125 the latch to throw the switch. In closing the switch, the action is as entirely automatic as it is in any latch without the lug 22; since the curved or inclined lower and rear sides of the lug 22 permit the nose 18 to pass 130

rearwardly over the upper side of the lever 6 very readily as said upper side travels downward past the nose. At the same time, the front side of the lug 22 being substantially straight, there is no danger of the lug slipping forwardly upward and away from its engagement with the rear side of the lever 6 when the lever 6 is in its raised position as indicated by the dotted lines in Fig. 10. Thus, it is at all times necessary to press downward upon the lever 6 as well as upon the treadle 15; and it will be readily understood that such simultaneous depressions are not liable to occur accidentally.

15 Having fully described my invention, what I claim as new and desire to secure by Letters Patent is:

1. A switch-stand latch to hold an operative part of the switch, and comprising a member movable across said operative part to release said part for operation of the switch, and means on said member to engage with said part and prevent the releasing movement of said member when said part lies against said member.

2. A switch-stand latch comprising receiving means to receive the switch-stand lever, a hook to swing over said lever when it is thus received, said hook and said receiving means being so positioned relative to said lever that said lever may move down in said means away from said hook or move up in said means against said hook, a mounting for said hook whereby said hook swings across said lever, and means extending down from said hook to engage with said lever when said lever is raised toward said hook whereby said hook is permitted to be withdrawn from said lever only upon pressing 40 said lever away from said hook.

3. A switch-stand latch comprising a housing having a crotch to receive the switch-stand lever down in it, a hook comprising a nose and pivoted in said housing to swing said nose across the top of said lever as it lies in said crotch, the lower side of said nose being far enough above the bottom of said crotch to permit said lever to swing up and down in said crotch when said nose is thereover, and a lug extending down from said nose to engage with a side of said lever when said lever is raised in said crotch and prevent said hook from swinging away from said lever, whereby said hook 55 is released to be swung away from said lever only upon first pressing said lever down from said nose.

4. A switch-stand latch comprising a housing having a crotch to receive the switch-stand lever down in it, a hook comprising a nose and pivoted in said housing to swing said nose across the top of said lever as it lies in said crotch, the lower side

of said nose being far enough above the bottom of said crotch to permit said lever to 65 swing up and down in said crotch when said nose is thereover, and a lug extending down from said nose to engage with a side of said lever when said lever is raised in said crotch and prevent said hook from swinging away 70 from said lever, whereby said hook is released to be swung away from said lever only upon first pressing said lever down from said nose, the side of said lug engaging with said lever being substantially straight and parallel with 75 said side of said lever, and the opposite side of said lug being inclined to permit said nose to readily slide over said lever as the lever passes down into the crotch past the nose.

5. A switch-stand latch comprising receiving means to receive the switch-stand lever, a hook to swing over said lever when it is thus received, said hook and said receiving means being so positioned relative to said lever that said lever may move down 85 in said means away from said hook or move up in said means against said hook, a mounting for said hook whereby said hook swings across said lever, means extending down from said hook to engage with said lever 90 when said lever is raised toward said hook whereby said hook is permitted to be withdrawn from said lever only upon pressing said lever away from said hook, and a treadle connected to said hook for withdrawing said hook from said lever by pressure of the foot while said lever is first depressed by one hand to permit said withdrawal, and then raised with said hand as permitted by said withdrawal. 100

6. A switch-stand latch comprising a housing having a crotch to receive the switch-stand lever down in it, a hook comprising a nose and pivoted in said housing to swing said nose across the top of said lever as it lies 105 in said crotch, the lower side of said nose being far enough above the bottom of said crotch to permit said lever to swing up and down in said crotch when said nose is thereover, a lug extending from said nose to engage with a side of said lever when said lever is raised in said crotch and prevent said hook from swinging away 110 from said lever, whereby said hook is released to be swung away from said lever only upon first pressing said lever down from said nose, and a treadle connected to said hook for withdrawing said hook from said lever by pressure of the foot while said lever is first depressed by one hand to permit said withdrawal, and then 115 raised with said hand as permitted by said withdrawal. 120
